UNITED STATES PATENT OFFICE.

GODFREY M. S. TAIT, OF MONTCLAIR, NEW JERSEY, ASSIGNOR TO TAIT PRODUCER COMPANY, OF NEW YORK, N. Y., A CORPORATION OF NEW JERSEY.

CHARGING-HOPPER.

992,697.

Specification of Letters Patent. Patented May 16, 1911.

Application filed January 11, 1910. Serial No. 537,383.

To all whom it may concern:

Be it known that I, GODFREY M. S. TAIT, a subject of the King of England, and a resident of Montclair, in the county of Essex and State of New Jersey, have invented certain new and useful Improvements in Charging-Hoppers, of which the following is a full, clear, and exact specification, such as will enable others skilled in the art 10 to which it appertains to make and use the same.

My invention relates to a charging hopper, especially designed for use in connection with gas producers, but applicable to 15 other similar structures.

Aside from the primary objects of constructing the hopper so that it will be durable, easy and satisfactory in operation, the principal object of the invention is to render the hopper gas-tight at all times and to insure, by automatic devices, that it will not be accidentally opened in such a way as to afford an opening from the interior of the producer into the atmosphere. I attain this 20 end by certain peculiar devices for mounting the dumping bell at the base of the hopper and by a certain lock device which coacts with the lid at the top of the hopper in such a manner that it automatically locks 25 the dumping bell at the base as soon as the lid is open. In this way when the lid is opened to fill the hopper I insure that the dumping bell discharging into the producer cannot be opened, although when the lid is 30 closed the dumping bell may be freely operated to discharge fuel into the producer.

My invention involves various other features of importance, all of which will be fully set forth hereinafter and particularly 40 pointed out in the claims.

For the purpose of an illustration of a specific form of the invention, the accompanying drawings represent, as an example, the preferred manner of practically embodying the same.

In these drawings:—Figure 1 represents a side view of the hopper with the dumping bell in open position; Fig. 2 a section thereof on the line 2—2 of Fig. 1; Fig. 3 a 50 section showing the lid open and the dumping bell closed; Fig. 4 is an exterior view of

the hopper, the line of vision being at right angles to that of Fig. 1; and Fig. 5 is a plan view of the hopper with the lid partly open.

10 indicates the body of the hopper, which 55 may be and preferably is provided with a tapering bottom portion 10^a having a discharge opening 10^b and a base flange 10^c, by which last-named part the hopper may be fastened on the head of the producer or 60 other apparatus in connection with which it is used.

11 indicates the dumping bell, which is of the usual tapering form and provided with a lug 12, to which a link or links 14 are articulated, and by which the bell is sustained. Said links in turn are sustained by an arm 15 fast on a rock-shaft 16 mounted in a box 17, formed on or fastened to the side of the hopper. By these devices the dumping bell 70 is sustained either in the closed position, shown in Fig. 3, or it may be dropped down to the lowered position, shown in Fig. 2. In the first position the tapering walls of 75 the bell engage the walls of the opening 10^c closing the hopper; and in the second position the bell is dropped away from said walls and allows the contents of the hopper, or any part thereof, to be charged into the producer. The rock-shaft 16 has its ends 80 fitted revolvably, yet snugly, in the side walls of the box 17, so that a practically gas-tight joint is effected at this point. One end of the rock-shaft 16 is slotted, as indicated at 16^a, for the purpose of the locking devices, 85 and will be hereinafter described. The other end has fast thereon an arm 18, carrying a counter-weight 19, whereby the bell 11 is normally held in closed position. By lifting the arm 18 inward and upward, however, 90 the bell may be lowered, as shown in Figs. 1 and 2, and the contents of the hopper, or any part thereof, charged into the producer.

20 indicates the lid of the hopper, which 95 is in the form of a circular plate and has at one end a lug 21 mounted by a vertical pin 22 on a corresponding lug 23 at the upper part of the hopper 10 at the side thereof. In this manner the lid may be moved in a horizontal plane to opened or closed 100 position. Extending diametrically across the upper side of the lid from the lug 21 is

a spring lock arm 25, one end of which is fastened by the bolt or pin 22 and the other end of which is confined within certain limits by a bridge 26. The bridge 26 is of inverted U-form and fastened in inverted position on the lid 20. At about the middle of the lock-arm 25 is a screw or other means 27 for adjusting the tension of the lock-arm. When the lid is closed the free end

10 of the arm 25 lies under a keeper 28 formed on or fastened to the side of the hopper 10 diametrically opposite the lug 23. The spring arm 25 engages this keeper and in so engaging it holds the lid in place. To move 15 the lid the spring arm should be first depressed, thus freeing the lid.

The lock device includes a lever 29, which is fulcrumed outside of the hopper on a pin 30, said lever being so disposed that it may 20 swing by gravity to perpendicular position from the inclined position shown in Fig. 1, in which perpendicular position it enters the slot 16^a of the rock shaft 16 and locks said shaft with its connections against movement. 25 The slot 16^a in said shaft 16 is so disposed that the lock lever will not enter the slot except when the discharging bell 11 is closed. Hence when the lock lever enters the slot 16^a it insures holding the charging bell 30 closed. The upper end of the lock lever projects to a position alongside of the keeper 28 and when the lid is closed a lug 20^a thereon engages on the upper arm of the lever locking lever and moves the arm to in- 35 active position, holding it there until the lid is opened. The instant the lid moves to open position the upper end of the lock-lever is disengaged and the lever is allowed to fall by gravity into engagement with the 40 walls of the slot 16^a of the shaft 16.

By these very simple, yet automatic devices, I insure absolute safety and reliability in the operation of the charging hopper, and prevent any possible leakage of gas or 45 ingress of air into the producer by reason of the charging thereof. The instant the lid is opened the dumping bell 11 is locked and cannot be opened until the lid is completely closed.

50 Having thus described my invention, what I claim as new, and desire to secure by Letters Patent of the United States, is:

1. A charging hopper having a discharging means at lower part of the hopper, a 55 swinging arm connected therewith, a rock-shaft on which the arm is carried, a box on the hopper and having the rock-shaft mounted therein, one end of the rock-shaft projecting beyond the box and means connected with said end of the rock-shaft to actuate it, the second end of the rock-shaft also projecting beyond the box, a locking means coacting with the second end of the 60 rock-shaft to prevent motion of the same 65 and of its connected parts and a lid at the

top of the hopper controlling said locking means.

2. A charging hopper having a discharging means, a normally active lock therefor and a closure for the hopper having a part 70 to engage the lock and hold it inactive while the closure is shut, whereby when the closure is opened the lock moves into action.

3. A charging hopper having a discharging means at the lower part thereof, a swinging arm connected therewith, a rock shaft on which said arm is carried, a pivoted member adapted to engage with said rock shaft for preventing the rotation of the latter, a cover for the upper end of said hopper and adapted to engage with said locking member to swing the latter to inoperative position as said cover is moved to closed position. 85

4. A charging hopper having a vertically movable discharge means at the lower part thereof, a horizontally movable cover at the upper end thereof and a locking member pivoted at the side of said hopper and having one end serving when in operative position to lock said discharging means in closed position and having the opposite end controlled by the movement of said cover, whereby the locking member is moved into 95 inoperative position upon the closing of the cover. 90

5. A charging hopper having a rock shaft extending through a side wall thereof, a discharging means at the lower portion of 100 said hopper and connected to said rock shaft, a locking member pivotally secured to the outer side of said hopper and adapted to engage with the outer end of said rock shaft for locking the discharging means in closed position and a closure for the upper end of said hopper independent of said locking member and adapted to engage with the latter to move said locking member into 105 inoperative position upon the closing of said closure. 110

6. A charging hopper having a discharging means at the lower part thereof, a rock shaft, connections between said discharging means and said rock shaft for operating the former upon the rocking of the latter, a movable member adapted to engage with said rock shaft to prevent the rocking of the latter, and a cover for the upper end of 115 said hopper and adapted to engage with said locking member to move the latter to inoperative position as said cover is moved to closed position. 120

7. A charging hopper having a discharging means at the lower part thereof, a rock shaft extending through the wall of said hopper and having a portion within the hopper and a portion outside thereof, connections between said inner portion of the rock shaft and said discharging means, a 125 130

movable locking member for engaging with the outer portion of said rock shaft, and a cover for the upper end of said hopper adapted to engage with said locking member to move the latter to inoperative position as said cover is moved to closed position.

In testimony whereof I have signed my name to this specification in the presence of two subscribing witnesses.
